SwitzerlandApplication August 27, 1937, Serial No. 161,195
In Switzerland September 22, 1936

5 Claims. (Cl. 123—173)

This invention relates to an improved cylinder for opposed-piston engines and has for its principal object the provision of a cylinder-liner having means for preventing local overheating of the liner. My invention makes it possible to maintain the temperature of the cylinder substantially uniform and the undesirable consequences of temperature inequalities are, therefore, largely eliminated.

- 5 10 In cooling opposed-piston engines, it is desirable to maintain the temperature of the cylinder walls as nearly uniform as possible in order to minimize heat stresses within the cylinder which will tend to impair the efficient operation 15 of the piston and piston rings. Lack of uniformity of the cylinder wall temperatures is due largely to the high temperatures created in the combustion chamber of the engine and to the relatively low temperatures prevailing at the 20 extremities of the cylinder. In apparatus heretofore proposed for cooling the cylinders of opposed-piston engines, the cooling effect or the rate of heat dissipation has been substantially uniform throughout the length of the cylinder. 25 Consequently that portion of the cylinder which surrounds the combustion chamber has been kept at a considerably higher temperature than the extremities of the cylinder, and internal heat stresses were inevitably created.
- 30 In an engine cylinder-liner in accordance with my invention, that portion of the cylinder-liner which surrounds, and is immediately adjacent to the combustion chamber, is provided with an annular projection or collar having channels for 35 the circulation of a cooling medium. The distance between these channels and the inner bore of the cylinder decreases and becomes a minimum as the channels approach the longitudinal center of the annular projection. The channels 40 may be shaped and positioned in various ways, for example, they may be angular and positioned so that their vertices are at substantially the longitudinal center of the annular projection or they may be straight and positioned obliquely 45 to the axis of the cylinder.

The constructional details of my invention are shown in the accompanying drawing, in which:

50 Fig. 1 is a sectional view, partly in section, of a cylinder assembly illustrating a cylinder-liner in accordance with my invention;

Fig. 2 is a view, partly in section, of a cylinder-liner illustrating another embodiment of my invention;

55 Fig. 3 is a section along the line 3—3 of Fig. 1;

Fig. 4 is a section along the line 4—4 of Fig. 2, and

Fig. 5 is a section along the line 5—5 of Fig. 2. As shown in the drawing, the cylinder-liner 1 is provided with a scavenging port 2 and an 5 exhaust port 3. The pistons 4 and 5 are shown in their outer dead-center positions. When the pistons are in their inner dead-center positions, the space between them serves as the combustion chamber of the engine. The cylinder-liner 10 is held in place by the flanges 8 of the cylinder jacket 7 which is provided with bores 6 within which suitable fuel valves (not shown) may be arranged.

A cooling medium, for example water, which 15 enters through the opening 16a and discharges through the opening 16b flows through the passages 9 and 10. These passages are connected to one another by the angular channels 13 and 14 in the collar or annular projection 18 which 20 encircles the combustion chamber. The channels 13 and 14 form a pair of inclined intersecting channels, and a plurality of such pairs of channels are formed in the annular projection. Those portions of the collar or annular projection 25 which are penetrated by the fuel and starting valves are provided with channels 11 and 12 which are connected together or by-passed by the space 15 surrounding these valves.

The angular channels 13 and 14 are inclined 30 toward the axis of the cylinder so that the distance between each of the angular channels and the inner bore of the cylinder becomes a minimum at substantially the center of the annular projection 18, i. e. the center with respect to the 35 length of the annular projection as determined, for example, by the position of the line 3—3 in Fig. 1 and line 4—4 in Fig. 2. Each of the angular channels slopes from each end towards the cylinder wall and the vertex is adjacent 40 to the center of the projection 18. The channels 11 and 12 are also angularly disposed and converge toward the inner bore of the cylinder, but this convergence is terminated 45 by the vertical extensions of the channels. The orientation of these various channels and channel extensions in the annular projection 18 may be readily determined by reference to Fig. 3.

In the embodiment of my invention shown in 50 Fig. 2 the channels 17 passing through the annular projection of the cylinder-liner 1 are arranged obliquely to the axis of the cylinder and are straight instead of being angular. The manner in which these channels 17 are placed in 55

the annular projection 18 is shown in Figs. 4 and 5.

As shown in the lower portion of Fig. 2, the channels 17 are nearest the inner bore of the cylinder where they approach the center of the annular projection 18. This is further illustrated by reference to Figs. 4 and 5 which show that each individual channel is at its minimum distance from the inner bore of the cylinder at substantially the center of the annular projection. On either side of this center, the distance between the inner bore of the cylinder and the channels increases. At those places where the annular projection is penetrated by the fuel and starting valves, the channels 17 are cut short and are by-passed in the same fashion as channels 11 and 12, shown in Fig. 1.

By maintaining the temperature of the cylinder wall substantially uniform, I am able to reduce and minimize the strains and stresses which result from non-uniform temperatures in the cylinder. While I have shown two embodiments of the invention by which a substantial uniformity of temperature may be attained in the cylinder-liner, I do not wish to be limited thereto, since my invention includes any construction of channel in the annular projection of the cylinder in which the distance between the channel and the inner bore of the cylinder decreases and becomes a minimum as the channel approaches the center of the annular projection.

I claim:

1. A cylinder-liner for opposed-piston engines having a collar or projection surrounding the combustion chamber of the cylinder, said projection being provided with a plurality of channels oblique to the axis of the cylinder for the circulation therein of a cooling medium, the

distance between said channels and the inner bore of the cylinder decreasing and becoming a minimum as the channels approach the center of the projection.

2. A cylinder-liner for opposed-piston engines 5 comprising a projection surrounding the combustion chamber of the cylinder, said projection having a plurality of angular channels for the circulation therein of a cooling medium each of which is inclined towards the inner wall of 10 the cylinder-liner and has a vertex at substantially the center of the projection.

3. A cylinder-liner as claimed in claim 1 in which the channels are by-passed at the places where the fuel and starting valves penetrate the 15 annular projection.

4. A cylinder-liner as claimed in claim 2 in which the channels are by-passed at the places where the fuel and starting valves penetrate the 20 annular projection.

5. A cylinder-liner for opposed-piston engines having a collar or projection on the outside thereof, the center of said projection embracing a plane at right angles to the longitudinal axis of the cylinder-liner and midway between the 25 pistons, a plurality of pairs of inclined intersecting channels in the projection for the circulation therein of a cooling medium which are so disposed that the points of intersection of the channels come closest to the inner wall of 30 the cylinder-liner near the said center, an opening in the liner projection for the mounting of valve means, other channels in the projection adjacent the opening, and a passage surrounding the opening connected to the other channels for 35 circulating cooling medium through the other channels and the passage.

CURT RETSCHY.
